OTTO HAENTJENS, OF HAZLETON, PENNSYLVANIA.

PUMP SYSTEM.

Application filed January 30, 1922. Serial No. 532,784.

To all whom it may concern:

Be it known that I, OTTO HAENTJENS, a citizen of the German Republic, residing at Hazleton, in county of Luzerne and State 5 of Pennsylvania, have invented certain new and useful Improvements in Pump Systems, of which the following is a specification.

My invention relates to pump systems, and specifically to a priming system for 10 centrifugal pumps, although certain features of the invention are applicable to other uses. One specific object of my invention is to provide a priming system in which the connection between the centrifugal and the 15 priming pump is made through a vacuum breaker which automatically unloads the priming pump after the centrifugal has been properly primed.

Another specific object of my invention 20 is to provide a priming system in which the priming pump is automatically relieved from the pressure of the discharge from the centrifugal after the latter has been started, although the priming pump continues in 25 action.

Another specific object of my invention is to provide a priming system in which the priming pump is kept dry even after the 30 centrifugal has been fully primed and started in operation.

Other objects of invention, as well as improvements in construction, will be hereinafter described or shown in the accompanying drawings, in which

Fig. 1 is a more or less diagrammatic side elevation of a priming system in which my invention is embodied in one form;

Fig. 2 is a vertical section through the 40 vacuum breaker of Fig. 1, but drawn to an enlarged scale; and

Fig. 3 is a similar view of a modified construction of the vacuum breaker.

It has become common practice, where circumstances permit, to utilize an auxiliary 45 pump of some sort for exhausting the suction pipe and runner chamber of a centrifugal pump to induce the rise of liquid through the suction pipe to the pump chamber, and thus to prime the centrifugal before the drive of the latter is started. The 50 practice is, however, attended with certain practical difficulties. Thus, all priming pumps, whether of the wet or dry type, handle only air until the runner chamber 55 of the centrifugal and its suction pipe are exhausted. The liquid rising into the can-

trifugal, however, passes through the line connected to the priming pump, with the result that the latter is suddenly called upon to handle a heavy liquid load. A severe strain 60 is thereby imposed on the motor of the priming pump, and where the latter is driven by a belt, the latter often jumps the motor pulley. The motor must of course be strong enough to pull the priming pump under the 65 liquid load. In the ordinary course of events, the attendant awaits the discharge of liquid from the priming pump as the signal for starting the centrifugal pump, and inasmuch as some time elapses before 70 the valve in the line between the priming and centrifugal pumps can be shut, the full discharge pressure of the centrifugal is transmitted to the priming pump. The latter must be of very heavy construction 75 therefore, when used in connection with a high-lift centrifugal. The valve in the connection between the pumps cannot be shut before the centrifugal is started, since the liquid must be maintained in the latter to 80 insure its priming, and if the priming pump is stopped before the centrifugal is started, air is apt to leak into the centrifugal pump chamber before the pump runner is sufficiently under way,—thus causing failure 85 of the priming operation. Furthermore, it is not practical to put an ordinary check valve between the centrifugal and the priming pump, because the check valve when once closed will not open again unless the 90 priming pump is first stopped and the vacuum destroyed. The present invention overcomes these difficulties.

Referring to Fig. 1, the centrifugal pump 5 has associated therewith the usual suction inlet 6 and delivery outlet 7. A pipe line 8 connected at 9 to the top of the centrifugal pump chamber, leads through a vacuum breaker, generally indicated by the reference 10, to a dry-operated priming pump 11. 95 This priming pump is preferably of the type shown in my copending application of even date, comprising a pair of working cylinders 12 and 13, to which the pipe line 8 opens through branch connections 14 and 15. 100 The particular form of vacuum pump, however, does not enter into the invention to which the present application is directed.

The vacuum breaker is indicated on a larger scale in Fig. 2, and comprises, as there shown, a float chamber 16, the lower portion 110 of which has a downwardly extending neck

17 for connection with the riser portion *a* of the pipe line 8 from the centrifugal 5. A port 18 in the upper portion of the float chamber is connected to the portion *b* of 5 the pipe line 8 leading to the priming pump. Within the float chamber is arranged a 10 float 19 and its associated lever 20 pivoted at 21 to the float chamber casting. A check valve 22 is hung at 23 from the float lever 20, and serves, on the rise of the float to close the port 24 through which air or liquid enters the float chamber 16 from the centrifugal 5. A second valve 25, pivoted at 26 to the float lever, normally closes the port 27 15 opening to air in the upper portion of the float chamber, and serving, when the valve 25 is opened, to admit air to the line 8 at a point beyond the port 24 through which 20 connection is established between the centrifugal and the float chamber. The particular location and means for operating this unloader valve 25 is unimportant, so long as it serves the function of admitting 25 air to the pipe line 8 after the centrifugal pump has been primed.

Preferably associated with the check valve 22 is a cylindrical housing 28 surrounding the body of the check valve, and of sufficient height to accommodate the latter in all positions. The lower end of the housing is preferably closed, but its sides are provided with vertical slots 29, through 30 which air and liquid from the centrifugal pump 5 are admitted under the suction effort of the priming pump. On the rise of 35 the check valve 22 in the housing 28, the area of the openings 29 above the valve is gradually diminished, thus reducing the admission to port 24 so that the check valve 40 comes very gently to its seat. As the bottom of the housing is closed, the housing also acts as a dash pot which prevents the jumping of the float and valve.

The operation of the system is readily 45 understood. When the priming pump is started, air is exhausted from the centrifugal pump 5 and its suction inlet 6, the air being drawn through the pipe line 8 without impediment since the float chamber 16 is empty, and the 50 float is in its lowermost position, thus holding the check valve 22 wide open and the unloader valve 25 closed. When the centrifugal pump is primed and the liquid rises through the portion *a* of the pipe line 8 into 55 the float chamber 16, the float 19 begins to rise, simultaneously lifting the check valve 22 toward closing position and the unloader valve 25 to open position. Air now enters the portion *b* of the pipe line 8 through the 60 unloader valve 25, thus reducing the vacuum in the float chamber and permitting the liquid to run back toward the centrifugal 5. The float 19 falls, thus bringing the unloader valve 25 nearer to its seat. The water 65 level in the float chamber promptly adjusts

itself so that the air entering through the unloader port 27 is equal to the capacity of the priming pump. When the attendant notices that the unloader valve 25 is lifted and that air is drawn in through the unloader valve port 27, he is thereby advised that the centrifugal pump is primed, and at once starts the latter. The drive of the centrifugal forces the liquid through the port 24 into the float chamber, thus causing 70 the float 19 to rise rapidly and lift the check valve 22 to its seat at the port 24, simultaneously opening wide the unloader valve 25. As the check valve 22 rises, the inlet slots 29 are gradually overrun, thus 75 restricting the inlet therethrough and permitting the valve to come to its seat gently. The priming pump, which continues to operate, now derives its entire supply of air through the unloader valve port 27, which 80 is of such proportions that a sufficient supply of air is admitted at this point to meet the capacity of the priming pump.

As soon as the centrifugal is running 85 properly, the connection between the pump chamber and the line 8 may be cut off by closing the gate valve 30. When it becomes necessary to again prime the centrifugal 5, the opening of the valve 30 automatically drains the float chamber and portion *a* of 90 the pipe line 8 so that the priming pump sucks only air when it resumes operation.

As above intimated, the particular arrangement of the float chamber and associated valves may be varied in many ways. 95 Such a variation is indicated in Fig. 3, in which the float 31 is guided by ribs 32 in a narrow float chamber 33, and has at its head a valve 34 adapted to close the port 35 upon the rise of the float. The unloader valve 36 100 is mounted on a stem 37 rising from the top of the float 31, and normally seated in the unloader valve port 39 which opens to a chamber 38 above the float chamber. The portion *b* of the line 8 to the priming pump 105 is connected to the chamber 38.

It will be clear from the foregoing that as soon as the centrifugal is properly primed, the rise of the float opens the vacuum breaker valve and unloads the priming 115 pump so that no liquid is drawn into the latter. Upon the closing of the check valve by the float, not only is the flow of liquid to the priming pump prevented, but also the pressure of the liquid under the drive of the 120 centrifugal is prevented from reaching the priming pump.

Various modifications of detail will readily occur to those dealing with the problem, which do not, however, depart from what I 125 claim as my invention.

I claim—

1. In a pump system, a centrifugal pump, a priming pump therefor, a check valve arranged in the connection between said 130

5 pumps, a float for operating the check valve, together with an unloader valve arranged in said connection between the check valve and the priming pump, and means for automatically opening the unloader valve when the centrifugal pump has been primed.

10 2. In a pump system, a centrifugal pump, a priming pump therefor, a check valve arranged in the connection between said pumps, a float for operating the check valve, together with an unloader valve arranged in said connection between the check valve and the priming pump, and operated by said float to open the unloader valve when the centrifugal is primed.

15 3. In a pump system, a centrifugal pump, a priming pump therefor, a check valve arranged in the connection between said pumps, an unloader valve arranged in said connection between the check valve and the priming pump, and float means for controlling said valves to at least partially close the check valve and at least partially open the unloader valve when the centrifugal is primed, and thus establishing an equilibrium condition preventing the flow of liquid to

the priming pump on its continued operation after the centrifugal is primed.

4. In a pump system, a centrifugal pump, a priming pump therefor, means automatically operative after the centrifugal is primed for at least partially relieving the vacuum created by the continued operation of the priming pump, while maintaining said centrifugal in primed condition, and means automatically cutting off connection between the priming and centrifugal pumps when the centrifugal is started.

30 5. In a pump system, a centrifugal pump, a priming pump therefor, check and unloader valve means arranged in the connection between the centrifugal and the priming pump, means for completely closing the check valve and completely opening the unloader valve under the pressure 35 of the discharge from the centrifugal after the latter has been started and while the priming pump is still running.

35 In testimony whereof I have signed my name to this specification.

40 OTTO HAENTJENS.
